FLUID DISPENSING DEVICE

Filed Feb. 16, 1949

UNITED STATES PATENT OFFICE

2,606,064

FLUID DISPENSING DEVICE

Halsey W. Taylor, Warren, Ohio, assignor to The
Halsey W. Taylor Company, Warren, Ohio, a
corporation of Ohio

Application February 16, 1949, Serial No. 76,831

3 Claims. (Cl. 299—9)

1

My invention relates to fluid dispensing devices, and more particularly to drinking fountains in connection with well-type water pumps, and the principal object of my invention is to provide new and improved apparatus of this character.

In ordinary well-type pump construction no provision is made for the dispensing of drinking of water, other than the attachment of a drinking cup to the pump. Obviously, this presents unsanitary conditions, since the cup is exposed to detrimental elements which may be suspended in the atmosphere, and still worse the one cup is used by a multitude of persons and such condition fosters the spreading of communicable diseases.

My invention provides an efficient and economically produced drinking fountain which may be used with a well-type water pump to avoid the disadvantages above mentioned, and to provide other sanitary features consistent with good drinking fountain manufacture. My invention has great application in areas where the only supply of water is from wells, and as examples, my invention may be used on farms, golf courses, and in rural districts.

Referring to the drawing which accompanies this specification and forms part of this application, there is shown, for purposes of illustration, an embodiment which my invention may assume, and in this drawing:

Figure 1 is a broken elevational view showing my invention as applied to a well-type water pump,

Figure 2 is an enlarged longitudinal section of a portion of the apparatus shown in Figure 1, and

Figure 3 is a longitudinal section corresponding generally to the line 3—3 of Figure 2, with parts shown in elevation.

Referring particularly to Figure 1 of the drawing, the apparatus herein shown to disclose the invention comprises a well-type pump 10 having a pump cylinder 11 disposed in the water of the well W. A tube 12 has fluid communication with the pump cylinder 11 and extends upwardly through the ground G and is threaded into the lower end of a receptacle 13, as shown at 14 (see Figures 2 and 3).

A reciprocable pump rod 15 is adapted to operate the piston means in the cylinder 11 in the usual manner, and this rod extends upwardly in spaced relation through the tube 12 and the receptacle 13, and has connection with a pump handle 16. Thus, operation of the pump handle

16 in the usual manner will cause reciprocation of the rod 15 and effect pumping action of the piston means in the cylinder 11, so that water is drawn upwardly in the tube 12 and delivered to the receptacle 13. Water rises in the receptacle 13 until it reaches the level of the lip 17 of the outlet spout 18, whereupon it flows outwardly of such spout. The entire apparatus may be held in position by a flange 19 which is slidable along the tube 12 and is bolted to this tube in position to engage the upper surface of the ground G, or the adjacent surface of a concrete apron which is sometimes provided in the area surrounding the pump.

My invention provides a drinking fountain which is automatically operable when water is delivered to the receptacle 13, water being delivered for drinking purposes when a certain level is reached in the receptacle, and flow of water continues in substantially uniform stream until the water in the receptacle drops to a certain lower level, whereupon the stream is generally abruptly interrupted.

As best seen in Figures 2 and 3, the receptacle 13 has an interior boss 20 formed at its lower end. The boss has a bore 21 which is threaded at its lower end to receive a bolt 22 which closes the lower end of the bore 21, and also forms means for the attachment of a bowl or catch basin 23. The bowl 23 has a drain passage 24 directed in the same general direction as the outlet spout 18 of the receptacle 13, so that waste water will not splash on the apparel of the user but rather is directed away from the user and may be collected in a drain 25 which may also collect waste water from the outlet spout 18.

Intersecting the bore 21 is a threaded opening 26 into which is threaded a water dispensing nozzle, such as the water bubbler 27 herein shown. The bubbler 27 has a hood 28 to protect the outlet nozzle from accumulation of dirt and other deleterious matter.

Secured within the upper end of the bore 21 (see Figure 3) is one leg 29 of a siphon tube 30, the right of the tube being disposed below the level of the lip 17 of the outlet spout 18 and merging with a downwardly extending leg 31. The leg 31 terminates within a bore 40 formed in a valve body 41, the lower end of the bore 40 communicating with the interior of the receptacle 13 at a point spaced from the bottom thereof. As will be clearly seen in Figure 3, the siphon tube 30 establishes a line of water communication between the interior of the receptacle 13 and the bubbler 27, and such line of

communication is formed with an opening to the atmosphere at its lowermost portion to provide escape for trapped air and a drain for water. In the embodiment shown, such escape opening is formed in the bubbler 27, as shown at 32, so that water may drain into the bowl 23.

The valve body 41 has a bore 42 intersecting the bore 40 and accommodating a valve plug 43 of the rotatable type. The plug 43 has a diametrically disposed aperture, so that passage of fluid through the bore 40 may be blocked at will. A nut 44 holds the valve body 41 in position with respect to the receptacle 13 and also clamps a dial plate 45 against the exterior surface of the receptacle. A valve rod 46 extends from the valve plug 43 and a pointer and operating handle 47 is connected to the exterior extremity of this rod. Suitable packing prevents leakage of fluid along the valve rod 46. The dial plate 45 is provided with spaced projections 48 and 49 which limit movement of the pointer 47 between the two positions of the valve plug 43. If desired, the plate 45 may be provided with the legend "Drink" adjacent to the projection 48 to indicate that the valve is open and that water will issue from the nozzle 27, and may also be provided with the legend "Pump" adjacent to the projection 49 to indicate that the valve is closed and only the spout 18 will issue water.

In operation, assuming the valve plug 43 is in "Drink" position, as water is pumped into the receptacle 13, the level of water will rise not only in the receptacle but also in the leg 31. When the level of water in the receptacle reaches the bight portion of the siphon tube 39, water will flow from the leg 31, through the bight portion, downwardly through the leg 29 and outwardly of the bubbler 27 in a stream as shown by the dotted lines S. The siphon action will thus be started, and water will continue to flow from the bubbler 27 until the level of the water in the receptacle 13 drops to uncover the lower end of the bore 40 which in effect is the lower end of the siphon-tube leg 31.

Continued pumping during the time the water is flowing from the bubbler 27 will cause the level of the water to rise above the bight portion of the siphon tube 39 so that water will flow from the outlet spout 18 in the event it is desired to collect water in a pail or the like. Any air in the siphon tube is readily vented through the opening 32, so that the flow of water from the bubbler is free of any sprays which otherwise may be caused by trapped air.

When pumping action has ceased, and the level of water in the receptacle drops to uncover the lower end of the bore 40, the siphon action will be broken to interrupt fluid flow from the bubbler 27. Water remaining in the bubbler 27, or in the leg 29 of the siphon tube 39, may drain through the opening 32 to the bowl 23. Water remaining in the receptacle 13 may be drained downwardly through the tube 12, and returned to the well W by means of a small opening 33 (see Figure 1) in the tube 12, which opening may be located below the frost line. Thus, when the apparatus is not in use, all water is automatically drained therefrom, and therefor no water remains in the apparatus and the possibility of damage done by freezing water is entirely eliminated.

It will be noted that the lower end of the bore 40 is some distance above the outlet end of the bubbler 27, so that a suitable head of water is provided even when the level of the water

approaches the lower end of the bore 40. This is desirable since it provides a stream of drinking water of sufficient height at all times so that the unsanitary danger present in contact of the user's mouth with the nozzle is avoided. Further, when the water level drops to uncover the lower end of the bore, the stream from the bubbler is interrupted abruptly, thus preventing the unsanitary danger involved in following a dwindling stream to the nozzle.

It has been found desirable to provide a valve for controlling flow of water through the siphon tube to further enhance the sanitary features of the drinking fountain. Without the valve, when a person is pumping water for disposal from the spout 18, the tendency is to cover the outlet of bubbler 28 with a finger, or otherwise close this outlet, and obviously this presents unsanitary conditions. The valve herein shown is located in full view of a person operating the pump handle 16, and it is an easy matter to turn the valve to desired position.

In view of the foregoing, it will be apparent to those skilled in the art that I have accomplished at least the principal object of my invention, and it also will be apparent to those skilled in the art that the embodiment herein described may be variously changed and modified, without departing from the spirit of the invention, and that the invention is capable of uses and has advantages not herein specifically described, hence it will be appreciated that the herein disclosed embodiment is illustrative only, and that my invention is not limited thereto.

I claim:

1. For use with a water pump having a receptacle into which water is pumped, said receptacle having an outlet opening and an outlet spout, a water drinking fountain comprising a siphon tube establishing fluid communication between the interior of said receptacle and said outlet opening, whereby fluid pumped into said receptacle flows through said siphon tube for drinking purposes and also through said outlet spout, and valve means for controlling fluid-flow through said siphon tube so that fluid-flow through said siphon tube may be interrupted when it is desired to dispense fluid through said outlet spout.

2. For use with a well-type water pump having a receptacle into which water is pumped and from which water is delivered through a spout opening, a water drinking fountain comprising a water dispensing nozzle carried by the lower end of said receptacle, a bent tube within said receptacle and providing siphon means, one leg of said tube being in communication with said nozzle and the other leg of said tube terminating an appreciable distance from the bottom of said receptacle so that a head of water is at all times maintained within said receptacle, valve means carried by a side wall of said receptacle and having a valve body disposed inwardly of said receptacle and having a port connected to the terminating end of said other leg and another port communicating directly with the interior of said receptacle, a valve plug movable within said valve body and operable to interrupt flow of water through said other leg and thus control operation of said siphon means.

3. For use with a well-type water pump having a receptacle into which water is pumped and from which water is delivered through a spout opening, a water drinking fountain comprising a water dispensing nozzle carried by the lower end of said receptacle, a bent tube within said receptacle and providing siphon means, one leg of said tube being in communication with said nozzle and the other leg of said tube terminating an appreciable distance from the bottom of said receptacle so that a head of water is at all times maintained within said receptacle, valve means connected to said valve plug and disposed exteriorly of said receptacle, the bight of said tube being disposed an appreciable distance above the lower end of said other leg so that an additional head of water equal to the height of said bight above the terminating end of said other

tube is required in said receptacle to start siphoning action of water from said receptacle to said nozzle, whereupon water issues in a substantially steady stream from said nozzle when said valve means permits flow of water through said siphon means and at a substantially uniform height and flow of water is interrupted abruptly when the level of the head of water uncovers said valve means so as to stop water flow before the stream of water appreciably diminishes in height.

3. For use with a well-type water pump having a receptacle into which water is pumped and from which water is delivered through a spout opening, a water drinking fountain comprising a water dispensing nozzle disposed exteriorly of said receptacle, a bent tube within said receptacle and providing siphon means, one leg of said tube being in communication with said nozzle and the other leg of said tube opening into said receptacle at a point spaced from the bottom thereof, the bight of said tube being disposed on a level sub-

stantially equal to the level of said spout opening so that water issuing from said spout provides visual indication to an operator that sufficient water is in said receptacle for proper siphoning action.
